(57) **CLAIM**

The ornamental design for an eyeglass frame, as shown and described.

DESCRIPTION

FIG. 1 is a perspective view of an eyeglass frame showing our new design;

FIG. 2 is a front elevational view thereof;

FIG. 3 is a top plan view, with the bottom view being a mirror image, thereof;

FIG. 4 is a right side elevational view, with the left side being a mirror image, thereof; and,

FIG. 5 is a rear elevational view thereof.

The broken line showing of the bridge and the temple portions in FIGS. 1-5 is for illustrative purposes only and forms no part of the claimed design.
